ATTORNEY:

UNITED STATES PATENT OFFICE.

THEODORE W. FOSTER, OF PROVIDENCE, RHODE ISLAND.

DESIGN FOR A COVER FOR BOXES OR SIMILAR ARTICLES.

No. 37,577.

Specification for Design.

Patented Oct. 24, 1905.

Application filed July 27, 1905. Serial No. 271,553. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for the Cover of a Box or Similar Article, reference being had to the accompanying drawing.

The figure in the drawing represents a top view of the cover of a box on the top of which is my design.

I claim—

The ornamental design for the cover of a box or similar article, as shown.

THEODORE W. FOSTER.
